SAFETY RAZOR

George Greenstein, Long Island, N. Y.

Application November 4, 1935, Serial No. 48,067

7 Claims. (Cl. 30—51)

The present invention relates to safety razors and has for its objects the provision of a simple, inexpensive device in which a wafer blade may be readily inserted and as readily removed; 5 which may be easily cleaned; which, while T-shaped when in use, may be arranged with the head and handle in parallel relation for occupancy of a minimum of space; which may be quickly disassembled for thorough cleaning and 10 readily reassembled for use; and in which the blade is positioned without contact of parts of the razor with the cutting edge thereof.

The above objects are attained by providing a head comprising two portions movable in relation to each other and separable, if desired, and pivotally connecting a handle to one of said portions whereby when the handle is arranged at right angles to the head, a blade is clamped between the two portions thereof. When the 20 handle is swung in one direction into parallel relation with the head, the two head portions are separated to free the blade for easy insertion or removal, and when swung in the other direction, the head portions are brought together 25 and retain their clamped relation.

The accompanying drawing, which is described in the following specification, more clearly discloses the various embodiments of the invention as at present contemplated.

30 In the drawing:—

Fig. 1 is a front view of a razor constructed in accordance with this invention as ready for use.

Fig. 2 is a vertical sectional view as taken 35 along the line 2—2 of Figure 1.

Fig. 3 is a similar view with the handle swung at right angles to free the blade.

Fig. 4 is an end elevational view of the razor shown in Figure 1.

40 Fig. 5 is a rear view of the razor showing details of the connection between the head and the handle thereof.

Fig. 6 is a similar view showing the manner of disengaging the handle from the head.

45 Fig. 7 is a plan view of a preferred form of blade.

Fig. 8 is a partial vertical sectional view of an alternate form of razor head.

In the present form of the invention the razor 50 comprises a head portion 10 consisting of a housing 11, a clamp and guard member 12, and a handle 13 normally arranged at right angles to the head.

The housing 10 is preferably formed with a 55 top 14, and walls 15, and a rear wall 16. The

clamp and guard member 12 is provided with trunnions 17 engaged in notches 18 in the end walls whereby the member 12 is tiltably and removably engaged in the housing 11. This member at its forward end is provided, in the 5 usual manner, with a guard portion 19 and a blade clamping portion 20. The rear portion 21 of the member 12 is off-set as at 22. This rear portion is also provided with an opening 23.

The housing 11 is preferably provided with 10 a down-reaching member 24 which passes through the opening 23 and terminates in an enlarged portion provided with a pivot hole for the accommodation of a pivot pin 25.

Also engaged on the pin 25 is the upper portion 26 of the handle 13 which is bifurcated to form the cam portions 27 and 28, the member 24 being positioned therebetween. Said member 24 is also provided with a notch 29 engageable by a spring-pressed detent 30 housed in the 20 handle.

The cam 27 is preferably formed with enlarged opposed portions 31 arranged transversely of the axis of the handle, and with a reduced portion 32 at the extreme upper end of the handle. 25 The cam 28 is preferably formed as a lug engageable with the plate 12 at its off-set 22.

In use, the handle is swung to the position shown in Figure 3, so one of the cam portions 31 engages the under side of the rear portion 21 of the plate 12 and thereby rocks said plate into the position shown in that figure. A blade B may now be dropped into the gap thus formed between the housing 11 and the plate 12, the rear edge 33 of the blade resting against the 35 inside face of the rear wall 16 of the housing.

In this manner, the cutting edge of the blade is not engaged or contacted by any portion of the razor when in use. In order to permit the blade to come to rest against the wall 16, the 40 blade is provided with a cut-out 40 which is necessary to avoid the member 24. The handle is then swung to the position shown in Figures 1 and 2, the cam lug 28 engaging the under face of the plate 12 at its off-set to rock the plate 45 about its trunnions so the portion 20 thereof clamps the blade against the under face of the housing top 14. The blade is now effectively positioned in the razor against displacement. In the above manner, the parts may be again 50 manipulated for the removal or replacement of a blade.

It will be noted that the cams 27 and 28 at all times control the movement of the plate 12, the cam 27 serving to open the head and 55

retain it open, and the cam 28 serving to close the head and retain it closed.

The detent 30 insures proper positioning of the handle during shaving and the off-set 22 in 5 the plate 12 permits the application of considerable clamping pressure by the cam lug 28 since said plate may flex slightly under the force of this pressure.

The razor structure, as above described, permits 10 of movement of the handle in either direction. At times it is desirable, however, to store the razor in a small space. For this purpose, therefore, one of the cam portions 31 may be omitted as shown in Figure 5 so the handle 13 may be swung in the 15 direction of the arrow 34 without moving the clamping plate 12. In this condition, a razor containing a blade may be carried, as for instance, in a convenient coat pocket. When it is desired to remove the blade, the handle is swung in the 20 direction of the arrow 35 and the action is as above described.

Ordinarily, it is sufficient to shake the razor after washing to free it of excess moisture before storing. However, at times it is necessary to 25 thoroughly clean all the razor parts. This is best accomplished when all the parts comprising the razor are disassembled. In the present instance disassembly of the parts may readily be done by providing the pivot pin 25 with flattened portions 30 36 which adapts said pin for movement along the open slot 37 in the member 24. When the handle 13 is thus removed, the plate 12 may be removed from association with the housing 11.

In the form of the invention shown in Figure 8, 35 the head is formed as an integral member comprising the top wall 11^a and the clamp and guard portion 12^a resiliently associated so that normally these portions are spaced (dotted lines) for the reception of a blade when the handle 13 40 is positioned parallel to the head, and are in clamped relation as shown when the handle is in right angled position. This structure provides a razor of extreme simplicity and durability which is quite economical to manufacture.

45 While the above is descriptive of the preferred embodiments of the razor as illustrated, it is apparent that immaterial changes in design may be made by skilled persons without departing from the scope of the invention as hereinafter 50 claimed.

What I claim as new and desire to secure by Letters Patent, is:

1. A razor comprising a head portion consisting of pivotally engaged members, and a handle for 55 the razor, pivotally connected to one of said members, said razor handle being provided with cam means for positively rocking the other of said members toward and away from blade clamping relation when the handle is rocked.

2. A razor comprising a head consisting of a housing and a blade clamping member pivotally associated therewith, a handle for the razor, pivotally connected to the housing, and cam means on the razor handle for positively rocking the clamping member into and out of blade clamping relation with the housing when the handle is rocked. 5

3. A razor comprising a head consisting of a housing and a blade clamping member pivotally associated therewith, a handle pivotally connected to the housing, cam means on the handle for engaging a rear portion of the clamping plate when the handle is swung in one direction, and cam means in the handle for engaging a front 15 portion of the clamping plate when the handle is swung in the other direction.

4. In a razor, a housing, a guard and blade clamping member pivotally connected with said housing, an extension on said housing, said guard and blade clamping member being formed with an opening for the protrusion of said extension, a handle pivoted to said extension, and cam means on said handle for rocking the guard and blade clamping member when the handle is 25 rocked on its pivot.

5. In a razor, a housing, a guard and blade clamping member pivotally connected with said housing, an extension on said housing, said guard and blade clamping member being formed 30 with an opening for the protrusion of said extension, a handle pivoted to said extension, cam means on the handle for moving the guard and blade clamping member into blade clamping relation with the housing, and cam means on the 35 handle for moving said member into blade releasing relation with the housing.

6. In a razor, a blade clamping head, comprising a housing and a blade clamping member pivotally associated with the housing, a handle 40 arranged substantially at right angles to said head when a blade is clamped between the housing and the clamping member, and means on the handle for positively moving the clamping member and thereby freeing the blade when said 45 handle is moved from the mentioned right angle position.

7. In a razor, a housing having a top, rear and side walls, a member pivotally connected to said housing and having a front blade clamping portion and a rear portion, a downwardly reaching extension on said housing, a handle pivoted to said extension, cam means on said handle engaged with the front blade clamping portion of the mentioned member, and cam means on 50 said handle engaged with the rear portion of said member, whereby upon movement of the handle about its pivot, the mentioned member is moved. 55

GEORGE GREENSTEIN.
